FIG. 1

FIG. 3

FIG. 2

FIG. 1 is a front view of a space condition responsive instrument as seen when looking directly at the face of the instrument;

FIG. 2 is a side view as seen from the right side of FIG. 1 with the instrument in its intended position of use, the other side being a mirror image thereof, the rear being plain or non-decorative in appearance; and

FIG. 3 is a fragmentary sectional view taken generally along the line 3—3 of FIG. 1 and from the same aspect as FIG. 2.

The dominant features of the design reside in the portions shown in full lines.

I claim:

The ornamental design for a space condition responsive instrument, substantially as shown and described,
